(57) CLAIM

The ornamental design for a container lid with utensil holder, as shown and described.

DESCRIPTION

FIG. 1 is a top perspective view of a container lid with utensil holder.

FIG. 2 is a top plan view of the container lid with utensil holder.

FIG. 3 is a left side elevation of the container lid with utensil holder.

FIG. 4 is a bottom plan view of the container lid with utensil holder.

FIG. 5 is a right side elevation view of the container lid with utensil holder.

FIG. 6 is a front elevation view of the container lid with utensil holder; and,

FIG. 7 is a back elevation view of the container lid with utensil holder.

The broken line showing is for illustrative purposes only and forms no part of the claimed design.
